COMPRESSOR UNIT

Harry B. Hull, Dayton, Ohio, assignor, by mesne assignments, to General Motors Corporation, a corporation of Delaware

Application June 30, 1930, Serial No. 465,022
Renewed January 6, 1934

8 Claims. (Cl. 230—29)

This invention relates to compressor units, and more particularly to motor-compressor units for use in refrigerating apparatus of this type.

In refrigerating apparatus of the compression type, it is customary to provide a compressor having its discharge side connected to a condenser and its inlet side connected to an evaporator, the discharge side of the condenser being in turn connected to the inlet side of the evaporator. Refrigeration is produced by evaporating a liquid refrigerant under reduced pressure in the evaporator, the vapors being compressed into, and condensed in a condenser under a considerably high pressure.

In order to maintain the evaporator, or the refrigerator which generally houses the evaporator, at a substantially constant temperature, it is customary to operate the compressor intermittently. That is to say, it is customary to start the compressor when the temperature within the evaporator increases to a predetermined high limit and to stop the compressor when the temperature falls to a predetermined low limit. Since the discharge side of the compressor is under condenser pressure and the inlet side of the compressor is under evaporator pressure, obviously the compressor must start under a heavy load, and consequently a motor having a high starting torque must be used, unless some means are provided whereby the motor and compressor are first permitted to attain predetermined speed before the load is applied thereto.

It is to such apparatus that my invention relates, having for one of its objects means for loading and unloading the compressor, whereby the compressor will be loaded only when it is driven at a predetermined high speed by its motor, and whereby the compressor will be unloaded when its speed is reduced below a predetermined minimum. More particularly it is an object of this invention, to provide an unloading device dependent for its operation on the presence of lubricating oil within the compressor lubricating system.

A further object of this invention is to provide, in refrigerating apparatus, a bypass extending between the high and low sides of said apparatus, and to provide means in said bypass for closing the said bypass to thereby load said compressor when the latter is driven at a predetermined high speed by its motor or other driving means. More particularly to provide an oil pump having its inlet in communication with the oil in the lubricating system of the compressor, and having its discharge side arranged to deliver oil to close a valve in said bypass when the oil pump, and consequently the compressor, is driven at a predetermined speed by its motor.

Further objects and advantages of the present

invention will be apparent from the following description, reference being had to the accompanying drawing, wherein a preferred form of the present invention is clearly shown.

In the drawing:

The figure is a diagrammatical view of a refrigerating system of the compression type, having incorporated therein a motor-compressor unit shown partly in section and partly in elevation.

In order to illustrate my invention, I have shown a refrigerating system of the compression type, having incorporated therein a motor-compressor unit embodying the features of my invention. For instance, I have shown a compressor, generally indicated by the reference character 10, connected on its discharge side to the condenser 11, through a conduit 12, a liquid receiver 13, and an evaporator 14. Refrigerant may flow through the parts in the order named. That is, refrigerant is compressed in the compressor 10, discharged through the conduit 12 into the condenser 11, where it is liquefied and finally collected in liquid form in the liquid receiver 13. From the liquid receiver 13, the refrigerant, in liquid form, passes through the conduit 15 to the evaporator 14. Herein the liquid refrigerant evaporates to produce a cooling effect, the vapors passing from the evaporator 14, through the conduit 16 to the crankcase of the compressor, as more fully set forth hereinafter. The motor 18 is connected to drive the compressor 10, and in order to maintain the temperature within the evaporator substantially constant, I provide means for starting and stopping the motor, and consequently the compressor, in response to predetermined high and low pressure conditions within the evaporator. To this end, a switch 20 is provided in the motor circuit 21, the switch 20 being operated by a bellows 22, which bellows is in open communication through a conduit 23 with the suction conduit 16. Thus the motor and compressor are controlled in response to predetermined high and low pressure conditions within the evaporator. In view of the fact that the pressure conditions within the evaporator vary directly with the temperature conditions therein, the motor-compressor unit is in reality responsive to the temperature conditions within the evaporator, or to the conditions within the refrigerator which generally houses the evaporator.

The evaporator 14 may be of any desired type. For instance, it may be of the float controlled flooded type similar to that disclosed in the patent to Osborn, No. 1,556,708, patented Oct. 13, 1925.

Referring in detail to the motor-compressor unit, I have shown this unit as including a plate 30, to which is secured by means of the bolts 60

31 a casting 32, forming a lower crankcase portion 33 and an upper cylinder portion 34. Within the cylinder 34 is mounted to reciprocate a piston 35, which piston is connected by means of a wrist 5 pin 36 to the pitman 37, the pitman 37 being in turn secured to, and enveloping the eccentric 38 secured on the drive shaft 39 and formed integrally with a counterbalance weight 40. The drive shaft 39 is journaled in the opposite aligned 10 bearings 41, 42, formed in the wall of the casting 32. This shaft 39 extends outwardly through the casting 32, as at 44, and has secured thereto a flywheel pulley 46, over which pulley, a belt, driven in the usual way by the motor 18, is 15 adapted to pass. A seal, or stuffing box, of any known type, is, of course, used to seal the shaft to prevent the escape of fluid into or out of the casing at the point when the shaft 39 passes through the casting 32. The upper portion of 20 the casting 32 is provided with a cutaway portion 48, within which cutaway portion fits a valve plate 50, the valve plate being provided with a passage 51, controlled by a valve reed 52, which valve reed 52 is normally held closed by a light 25 leaf spring 54 secured to the valve plate 50 by the screw 55. Above the valve plate a cylinder head 60 provided with a chamber 61 forming a high pressure chamber, is secured to the casting 32 by means of the bolts 62, and between the 30 cylinder head and the casting 32 is provided a confined lead gasket 66. The inlet to the compressor is provided through the crankcase, and to this end an opening 68 is provided in the wall of the casting 32 whereby the refrigerant 35 from the evaporator may pass into the crankcase 33 of the compressor. An inlet valve 69, herein shown as of the disc valve type, is provided in the head of the piston.

Thus, as the compressor operates, refrigerant 40 in vapor or gaseous form, is drawn through conduit 16 into the crankcase 33 of the compressor. On the downstroke of the piston 35, refrigerant passes from the crankcase through the inlet valve 69 to fill the cylinder 34. On the upstroke of 45 the piston, the refrigerant is compressed until the pressure of the refrigerant within the cylinder 34 exceeds the pressure of the refrigerant within the chamber 61 plus the slight pressure of spring 54, whereupon the compressed refrigerant is forced past the valve 54 into the high pressure line. This cycle is constantly repeated.

Means are provided for lubricating the compressor, and in this modification this means is shown as including a body of oil in the crankcase and an oil pump having its inlet side below the level of oil in the crankcase and its discharge side connected to various ducts leading to the bearings and wearing surfaces of the compressor. For instance, an oil pump 100, herein shown as 55 of the eccentric type, is provided on the end of the drive shaft 39 of the compressor. A conduit 102 communicates at one end with the inlet passage 103 to the oil pump 100 and at its other end communicates through a strainer 104 with the body of oil in the crankcase of the compressor. A passage 106 in the drive shaft communicates with the chamber 108 into which chamber the oil pump discharges, and lateral passages 107, in communication with the passage 106 in the drive 60 shaft 39, are provided for conveying lubricant to the bearings 41, 42 of the drive shaft 39. A passage 110, provided in the pitman rod 37, is in communication at one end with the passage 106 in the drive shaft 39, and at its other end is in 70 communication with a passage 111 extending

through the wrist pin 36. Lateral passages 112 are also provided in the wrist pin 36 for conveying lubricant from the passage 111 to the sides of the wrist pin 36. Thus the various parts of the compressor are lubricated by a forced feed 5 lubricating system, the lubricant being withdrawn from the crankcase 33 of the compressor and forced by the oil pump 100 through the various enumerated passages to the wearing surfaces of the compressor.

In order to provide means whereby the compressor may attain its normal running speed before its load is applied thereto, and to provide means whereby the compressor will be unloaded should its speed be reduced below a predetermined minimum, I have disclosed means operating in conjunction with the lubricating system for equalizing the pressure on both sides of the compressor piston, and for maintaining said equalized pressure condition until the compressor 15 is driven at a predetermined or normal running speed. For instance, in the walls of the casting 32 I have provided a passage 120 having its upper end communicating through a passage 121 with the interior of the cylinder 34, just below the valve plate 50, and having its lower end in communication with the crankcase 33 of the compressor. At its upper end, the passage 120 is provided with a valve seat 122, and a valve 124, the stem of which extends downwardly through the passage 120 into a pocket 126 in a piston 128, which piston slides within a cylinder 130 formed integral with the casting 32. Within the pocket 126, a spring 134 has its lower end bearing against the piston 128 and its upper end secured to the bottom of the valve stem. A passage 138 has one end in communication with the cylinder 130 and its other end in communication with the chamber 108 whereby oil discharged by the oil pump 100 may pass to the cylinder 130 beneath piston 128 40 to force the valve 124 against its seat 122. An oil pressure relief port 140 is provided in the walls of the cylinder 130 whereby excess oil pressure may be vented to the crankcase.

In operation, assume the compressor is idle 45 and the valve 124 is open. As the compressor starts, during the first few reciprocations of the piston 35, the refrigerant gas will pass from the cylinder 34 through the passages 121 and 122, past the open valve 124 back to the crankcase, 50 the compressor thereby running unloaded. As the motor speeds up, the oil pump 100 speeds up, gradually producing sufficient oil pressure to push up the piston 128 to close valve 124. The compressor then becomes loaded.

Should the speed of the motor or compressor be reduced, the oil pressure will be insufficient to hold piston 128 in its upper position. Consequently, the piston falls and the valve 124 opens, thereby allowing the compressor to run idle. 60 Also, when the compressor stops, the oil within the cylinder 130 immediately escapes through the various bearings to the crankcase, thereby allowing the piston 128 to drop and permitting the spring 134 to open the valve 124, to unload 65 the compressor.

Thus I have disclosed a compressor having incorporated therein a loading and unloading device depending for its operation upon the presence of lubricating oil within the compressor lubricating system. Should the quantity of lubricant become diminished below a safe margin, due to any cause whatever, the oil pressure generated by the oil pump will be insufficient to close the inlet valve and consequently the valve 70 75

122 will open, allowing the compressor to run idle. This idle running of the compressor will indicate to the operator that something is wrong with the compressor. Further, I have disclosed 5 an unloading device operating in conjunction with a compressor whereby during the starting of the compressor the load applied thereto will be zero, the compressor not even having to overcome the slight pressure exerted by the outlet valve in 10 the valve plate. In addition, I have disclosed apparatus which not only actuates the loading and unloading device of the compressor but also forces the lubricant to the various bearings of the apparatus.

15 While the form of embodiment of the invention as herein disclosed, constitutes a preferred form, it is to be understood that other forms might be adopted, all coming within the scope of the claims which follow.

20 What is claimed is as follows:

1. In a motor-compressor unit, a compressor and a motor for driving said compressor, said compressor including a cylinder, a piston in said cylinder, an inlet valve in the head of the said piston, a valve plate at the upper end of said cylinder, said valve plate including a discharge valve, and said compressor including means for unloading said compressor whereby its normal running speed may be attained before it becomes 25 loaded, said last named means including a by-pass communicating with the upper end of said cylinder below said valve plate and with the crankcase of the compressor.

30 2. In a motor-compressor unit, a compressor and a motor for driving said compressor, said compressor including a cylinder, a piston in said cylinder, an inlet valve in the head of the said piston, a valve plate at the upper end of said cylinder, said valve plate including a discharge 35 valve, and said compressor including means for permitting said compressor to attain its normal running speed before it becomes loaded, said last named means including a by-pass communicating with the upper end of said cylinder be- 40 low said valve plate and with the crankcase of the compressor, and means in said by-pass for closing said by-pass when the compressor is driven at a predetermined high speed by said motor.

45 3. In a motor compressor unit, a compressor and a motor for driving said compressor, said compressor including a cylinder, a piston in said cylinder, an inlet valve in the head of the said piston, a valve plate at the upper end of said cylinder, said valve plate including a discharge 50 valve, and said compressor including means for permitting said compressor to attain its normal running speed before it becomes loaded, said last named means including a by-pass commun- 55 icating with the upper end of said cylinder below said valve plate and with the crankcase of the compressor, and an oil pump and a pressure-operated valve in said by-pass responsive to the pressure from said oil pump for closing said by-pass.

60 4. In a motor-compressor unit, a compressor and a motor for driving said compressor, said compressor including a cylinder, a piston in said cylinder, a crankshaft operatively connected to 65 said piston, an inlet valve in the head of the said

piston, a valve plate at the upper end of said cylinder, said valve plate including a discharge valve, and said compressor including means for permitting said compressor to attain its normal running speed before it becomes loaded, said 5 last named means including a by-pass communicating with the upper end of said cylinder below said valve plate and with the crankcase of the compressor, and an oil pump and a pressure-operated valve in said by-pass responsive to the 10 pressure from said oil pump for closing said by-pass, said oil pump being located at the end of said crankshaft.

5. In a motor compressor unit, a compressor and a motor for driving said compressor, said 15 compressor having a low pressure side and a high pressure side, a cylinder, a piston in said cylinder, an inlet valve for said cylinder, a valve plate at the upper end of said cylinder, said valve plate including a discharge valve, and said 20 compressor including means for permitting said compressor to attain its normal running speed before it becomes loaded, said last named means including a by-pass communicating with the upper end of said cylinder below said valve plate 25 and with the low pressure side of the compressor, and means for closing said by-pass when the compressor has attained normal running speed.

6. In a motor-compressor unit, a compressor and a motor for driving said compressor, said 30 compressor having a high pressure side and a low pressure side and including a cylinder, a piston in said cylinder, an inlet valve for said cylinder, a valve plate at the upper end of said cylinder, said valve plate including a discharge 35 valve, and said compressor including means for unloading said compressor whereby its normal running speed may be attained before it becomes loaded, said last named means including a by-pass communicating with the upper end of said 40 cylinder below said valve plate and with the low pressure side of the compressor.

7. In a motor compressor unit, a compressor and a motor for driving said compressor, said compressor having a low pressure side and a high 45 pressure side, a cylinder, a piston in said cylinder, an inlet valve for said cylinder, an outlet valve for said cylinder, said compressor including means for permitting said compressor to attain its normal running speed before it becomes loaded, said 50 last named means including a by-pass in unrestricted communication with said cylinder interiorly of said outlet valve and communicating with the low pressure side of said compressor, and means for closing said by-pass when the 55 compressor has attained normal running speed.

8. In a motor compressor unit, a compressor and a motor for driving said compressor, said compressor having a low pressure side and a high pressure side, means defining a compressor 60 space, a compressing element for varying the volume of said compressor space, an outlet port for said space, said compressor including means for permitting said compressor to attain its normal running speed before it becomes loaded, said 65 last named means including a by-pass in communication with said space interiorly of said outlet port and communicating with the low pressure side of said compressor.
